US0D1075029S

(12) **United States Design Patent** (10) **Patent No.:** **US D1,075,029 S**
(45) **Date of Patent:** **** May 13, 2025**

(54) **THERMAL THERAPY INSTRUMENT**

(71) Applicant: **Solana Health, Inc.**, Del Mar, CA (US)
(72) Inventor: **David McMahon**, Del Mar, CA (US)

(73) Assignee: **OcuSci, Inc.**, Del Mar, CA (US)

(**) Term: **15 Years**

(21) Appl. No.: **29/800,905**

(22) Filed: **Jul. 23, 2021**

(51) LOC (15) Cl. **24-01**
(52) U.S. Cl.
USPC **D24/206**

(57) **CLAIM**

The ornamental design for a thermal therapy instrument as shown and described.

DESCRIPTION

FIG. 1 is a perspective view of a thermal therapy instrument showing our new design;

FIG. 2 is a left view of the thermal therapy instrument shown in FIG. 1;

FIG. 3 is a right view of the thermal therapy instrument shown in FIG. 1;

FIG. 4 is a rear view of the thermal therapy instrument shown in FIG. 1;

FIG. 5 is front view of the thermal therapy instrument shown in FIG. 1;

FIG. 6 is a bottom view of the thermal therapy instrument shown in FIG. 1; and,

FIG. 7 is a top view of the thermal therapy instrument shown in FIG. 1.

The broken lines shown in the figures illustrate portions of the thermal therapy instrument that form no part of the claimed design.
